FOOTWEAR

William H. Joyce, Jr., Pasadena, Calif., assignor
to The Pasadena Slipper Co., Inc., Pasadena,
Calif., a corporation of California

Application January 3, 1934, Serial No. 705,046

6 Claims. (Cl. 12—142)

My invention relates to improvements in footwear construction and a method of manufacturing the same. It is especially advantageous as applied to low shoes such as slippers.

- 5 Broadly speaking, the invention consists in performing a padded insole unit around and to which the "upper" is thereafter lasted right side out in such a manner that stitching may be dispensed with as a means for uniting said parts.
- 10 The invention lends itself to various types of footwear such as the low heel type, the higher heel type, and the sandal type.

15 My object is to provide a method of construction which will produce economically a shoe possessing long wearing qualities by reason of the fact that a heavier outsole can be successfully employed than has hitherto been possible in slippers of the padded sole variety in which stitching and turning has hitherto been regarded as essential, and which necessarily called for a thin light-weight sole material.

20 Another object is to construct a slipper that will possess the comfort features of a padded sole slipper while at the same time possessing the 25 appearance of a more expensive hard soled slipper.

25 Again, by reason of the fact that the padded insole unit, which in the preferred form includes a sock lining, is permanently built into the slipper, shuffling and loosening of the sock lining with the attending discomfort associated therewith is avoided.

30 A further object is to provide, at a minimum of expense, a slipper construction of the padded sole type, which simulates in appearance the 35 more costly type. These and other advantages will be appreciated and understood by the mechanic skilled in this art from a reading of the following description and an examination of the accompanying drawings in which I have set forth my invention in certain preferred forms.

40 In said drawings—

45 Fig. 1 is a perspective view of a finished slipper or shoe of the higher hard heel type, portions being broken away;

Fig. 2 is a side elevation of the slipper shown in Fig. 1, certain portions being broken away and shown in section;

50 Fig. 3 is a cross-section on the line 3—3 of Fig. 2;

Fig. 4 is a cross-section on the line 4—4 of Fig. 2;

55 Fig. 5 is a perspective view of an assembled padded insole unit for the type of slipper shown in Fig. 1;

Fig. 6 is a side elevation of my invention as applied to open or sandal type slipper;

Fig. 7 is a cross-section of the insole on the line 7—7 of Fig. 6;

Fig. 8 is a side elevation of my invention as applied to the padded sole type of slipper having a soft low heel, a portion being broken away.

10 1 represents the sole portion of the padded insole unit, which portion is made of any suitable material such as buckram. 2 represents a soft padding of suitable material such as felt, the same being permanently secured upon the portion 1. 3 represents a sock lining of appropriate material. In that form of the invention shown in Figs. 1 to 5, the parts 1 and 3 are stitched together along their edges to securely hold the padding 2 in place therebetween and so as to form a single padded insole unit. The sock lining and padding terminate short of the extreme rear end or heel portion of the sole 1 when the padded 20 insole unit is for slippers of the wood heel type. 4 is a metallic shank stiffener usually of steel which constitutes part of the assembled unit when the slipper is to be of the aforesaid type. 5 is a cover for the stiffener 4, said cover being made of 25 suitable material such as tough sheet fibre. The rear portion of this cover 5 is shaped to the contour of that part of the sole 1 to the rear of the padding 2 and serves the useful purposes hereinafter described. The shank piece 4 and cover 30 5 are mechanically secured to each other and to the sole 1 by any suitable means such as clinched staples which may straddle the piece 4 to hold it in place. 2' represents a piece of padding which constitutes the heel pad the same being of 35 the proper thickness and shape to cover the exposed portion of the shank cover 5. This piece 2' is suitably secured thereto as by cement and is provided with a sock lining 2'' for the heel, which preferably overlaps the sock lining 3 for the 40 shank when the slipper is completed as shown in Fig. 1.

45 As to the method of construction: Starting with a unit such as shown in Fig. 5, said unit (minus the part 2') is tacked onto the bottom of a last. Cement is applied to the margin of the unit on the exposed side before or after tacking the same to said last. When the upper has been fitted and is ready, the same is subjected to the lasting operation and the lasting allowance 6—6 50 is secured to the insole margin by any suitable means such as cement, staples, or otherwise. In that form of the invention shown in Figs. 1 to 5, it is contemplated that a counter will be used, the same being indicated at 7 (Fig. 4). Before the 55

heel padding 2' is applied, the quarter portion of the upper with the counter assembled therein may be lasted and clinched to the rear portion of the insole in the usual manner, as by clinched 5 tacks or nails 1—1. The parts at this stage are now ready to be prepared for the usual outsole laying operation. When prepared the outsole 8 is applied and securely and permanently attached by any appropriate adhesive process employing 10 preferably a powerful waterproof cement. The last is then removed. 9 is a hard heel, preferably of wood, which is secured in place by any suitable mechanical fasteners such as screws or nails 15 10—10 which may be driven through the rear portion of the piece 5. The pad piece 2' and the lining 2" are then securely cemented in place.

In Fig. 6 I have shown a modification of my invention as embodied in a slipper of the open or sandal type, and in which it is highly important 20 that the padded insole unit should present a finished appearance at the edges and throughout the area exposed to view through the open sides. In such a type of slipper, instead of uniting the members of the unit around the edges by over- 25 stitching, such as shown in Fig. 5, I employ any method which provides a smooth exposed edge. Such a padded insole unit is shown in Fig. 7, wherein instead of securing the edges of the sole portion and sock lining by means of over- 30 stitching, I provide a stripping 11 around the edge of said insole, which covers the edge of the padding and is suitably secured to said sole portion and sock lining, thereby furnishing a smooth finished edge for the insole unit. 12 represents 35 stitches which constitute one means for securing the stripping 11 to the sole portion and the sock lining. Inasmuch as the preformed padded insole unit should be tacked to the last before the upper is lasted, and inasmuch as the upper is 40 sometimes temporarily tacked to the insole, it is obvious that the removal of these tacks would leave holes in the sock lining, which, in the case of a high class sandal type slipper or shoe, would be objectionable. I may avoid this during the 45 preliminary operation by using a piece of inexpensive material in place of high-grade sock lining material, and a lining of proper material might be cemented in place as a final operation. In some cases, the preformed padded insole unit 50 might comprise the sole 1 and a pad 2 permanently secured together as by adhesive or stitches, in which event, if desired, a sock lining could later be secured in place.

Fig. 8 represents my preformed padded insole unit as applied to a slipper having a low soft heel, that is, not to be attached by nails or screws. In this case, the shank piece 4 and cover 5 are omitted, and the padding 2 may be of one piece extending from end to end of the insole. As in the 55 previous cases, the upper is lasted right side out on the preformed padded insole unit and the lasting allowance is gripped between the margins of the insole and outsole as previously indicated.

In all of the above forms, the area on the lower 60 side of the insole 1 within the edges of the lasting allowance may be filled in flush with the surfaces of the latter by a suitable strip of material of the proper thickness and outline so as to give the proper bearing for the outsole, such a filling 65 being indicated at 14.

I claim:

1. As an article of manufacture, a shoe comprising, a preformed padded insole unit composed of an insole piece outlined to the shape of 70 the sole and heel portions of the shoe, a metallic

shank stiffener supported longitudinally thereon in the region of the arch, a shank cover comprising a piece of hard sheet material, the rear portion of which is shaped to the outline of the heel portion of the insole with means mechanically securing together said parts, a padding outlined to cover the surface of said insole and shank cover but terminating short of the heel section of said cover, a sock lining above the padding and secured at its margin to the margin of the insole, an upper fitted and lasted to said unit, the lasting allowances being secured to the insole entirely around the edge of the same, that part of the lasting allowance underneath the heel portion of said shank cover being secured thereto by a mechanical means, a hard heel secured to the underside of the insole by means of mechanical fastenings which penetrate the heel portion of the shank cover, an outsole adhesively secured to the underside of the shoe and overlapping the adjacent portions of the lasting allowance, and a soft heel pad overlying and secured to the heel portion of the shank piece cover, and a covering for said heel padding.

2. As an article of manufacture, a sandal type 25 shoe comprising, a preformed padded insole composed of an insole piece, a padding supported thereon, a sock lining overlying said padding, a piece secured at its upper and lower edges respectively to said sock lining and insole piece to 30 secure all of said parts together to form said padded insole unit, a fitted upper lasted to said insole unit with the lasting allowance overlapping the outside margin of said insole and secured thereto, said upper having openings in the side 35 exposing the edge of said unit, an outsole covering the outer side of the insole and overlapping the lasting allowance and permanently secured to the latter by adhesive.

3. As an article of manufacture, a shoe comprising, a preformed padded insole unit composed of an insole piece outlined to the shape of the sole and heel of the shoe, a padding covering all but the heel end of said insole piece, a sock lining shaped to cover the padding and secured 45 at its edges to the corresponding edges of the insole piece, a metallic shank stiffener located longitudinally of the shank of the insole unit, a cover therefor secured thereto and composed of a sheet of fiberlike material shaped at its rear end 50 to the outline of the heel portion of the insole piece, a fitted upper including a counter lasted to said insole piece, the lasting allowances being secured to the margins of said insole piece entirely around the same and including mechanical fastenings in the heel zone, a hard heel secured to the underside of the heel portion by mechanical fastenings passing through said shank cover, and an outsole secured by adhesive 55 to that part of the shoe forward of the heel, the 60 margins of said sole overlapping the adjacent margins of the lasting allowance.

4. The method of manufacturing a shoe comprising, providing a separate padded insole unit comprising an insole piece, a metallic shank stiffener disposed longitudinally thereon in the region of the arch, a shank cover of hard sheet material overlying said shank and shaped at its rear to the outline of the heel portion of the insole, a padding covering that portion of the insole forward of the heel portion of the shank cover, all 65 of said parts being connected together as a unit, then lasting an upper to said insole right side out, and securing the lasting allowance of the upper to the outside margin of said insole en- 70 75

- tirely around the latter using mechanical fastenings at the margin of the heel portion of the shank cover, then securing an outsole and a hard heel to the bottom of the insole to cover the lasting allowance using mechanical fastenings passed through the heel portion of the shank cover for securing the heel in place, then covering the heel portion of the shank cover with padding and covering the latter with a lining.
- 10 5. An article of manufacture comprising a pre-formed padded insole unit composed of at least three layers of material including an insole piece, a sheet of padding supported thereon, a sock lining overlying said body and stitched at its margin to the margin of said insole piece, an upper lasted right side out to said unit with the lasting allowance enveloping the stitched margins of said in-
- sole piece and sock lining and secured by adhesive to the insole piece in the field within its stitched margin, and an outsole piece secured by adhesive to said lasting allowance and said insole.
6. The method of manufacturing a shoe comprising providing an insole piece, then placing thereon a sheet of padding, then placing a sock lining over said padding, then securing together the edges of said insole piece and sock lining, then lasting an upper right side out to the insole unit thus formed, then permanently securing by adhesive the lasting allowance of said upper to the lower margins of said insole unit, then permanently securing by adhesive an outsole to said assembled insole and upper.
